UNITED STATES PATENT OFFICE.

JACOB DAVID WOLF, OF LONDON, ENGLAND.

ORE-CONCENTRATING APPARATUS.

1,310,492.

Specification of Letters Patent. Patented July 22, 1919.

Application filed August 10, 1914. Serial No. 856,119.

To all whom it may concern:

Be it known that I, JACOB DAVID WOLF, a citizen of the United States of America, residing at 17 Throgmorton avenue, in the city of London, England, have invented certain new and useful Improvements in Ore-Concentrating Apparatus, of which the following is a specification.

The present invention relates to a new or improved values collecting element for ore concentrating apparatus.

It has already been proposed by me and others to employ in a wet concentration process an endless traveling belt coated with a grease, viscous oil, or the like, and impart a shaking motion to said belt, but all such apparatus have not hitherto been entirely commercially successful, principally owing to the difficulty and expense experienced in separating the metal or valuable portions from the grease or oil employed. By means of the present invention these difficulties are not only entirely overcome but it is possible to treat slimes not capable of being treated in any other way, and moreover certain metals or materials occurring naturally in a combined state can be efficiently separated by this invention, for instance in a low grade lead and zinc ore, or tailings from similar ores, the values can be readily concentrated and separated.

In all cases separation and concentration are effected with a minimum amount of wash water and the pulp may be warmed or heated without prejudicially affecting the operation.

The present invention comprises essentially a belt prepared in the manner hereinafter specified, whereby the metal or valuable portion is not coated or mixed with the oil yet—in conjunction with the special belt-shaking apparatus employed—an entire separation from the gangue is easily effected.

In the accompanying drawing,

Figure 1 is a view in side elevation of an apparatus constructed according to the present invention,

Fig. 2 is a view in plan thereof, and

Fig. 3 is an end view thereof.

Throughout the views similar parts are marked with like letters of reference.

The apparatus comprises essentially a table *a*—which may or may not be laterally inclined—adjustably carried on a suitable framing *b*, spring lath supports *c* for said table arranged to allow for longitudi-

nal, lateral, and slight up-and-down vertical movement thereof—in some cases additional laths *c*¹ may be provided—an endless belt *d* carried over and under said table, 60 supporting and driving rollers *e* *e*¹ for said belt, means such as *f* for tensioning said belt, means for oiling said belt comprising an oil tank *g*, oil pump *g*¹, delivery pipe *g*², and scraper *g*⁴ or other convenient oil distributing arrangement, adjustable eccentric gear *h* for imparting a longitudinal to-and-fro movement to the said table and therefore to the continuously traveling belt, and adjustable drag link gear *i* arranged to give 70 a lateral or other to-and-fro shaking movement to the said table and belt. Screw jacks *k* are preferably employed to provide adjustment for the framing *b*, which is free to pivot on trunnions *b*¹ so as to vary the 75 inclination of the table *a* in any desired way while in operation. The usual means employed in separating apparatus of the traveling belt type are provided for adjusting the eccentric and drag-link gear, for 80 feeding the pulp and wash water on to the belt and for removing the concentrates from the belt.

The main shaft *l* driven by means of a pulley *l*¹ is mounted in suitable bearings on 85 the frame *b* and is connected at one end to the drag link gear *i* the lateral motion of which is transmitted to the table through a rod *i*¹. On the other end of said shaft is a bevel wheel *l*² driving a similar wheel *m* 90 carried by a shaft *m*¹ mounted in suitable bearings on the frame and arranged at the feed end of the apparatus. The belt *d* is driven from the roller *e*¹ by means of a belt pulley *e*². The shaft *m*¹ carries the adjustable eccentric gears *h* both of which are adjustable by means of a hand wheel *h*² carried by a bracket on the frame. This hand wheel carries a sleeve provided internally 95 with a right and left hand thread adapted to engage corresponding threads on the ends of a divided rod *h*³, the free ends of which are connected to rocking levers for adjusting the throw of the eccentric disks. The eccentric straps are connected by rods *h*⁴ 100 to the table. The decking or table *a* is preferably provided with a diagonal front edge as shown in Fig. 2.

It will be understood that if the apparatus is designed to treat only one particular class 110 of material or to separate one specific grade of ore it will not be necessary to provide

means for adjusting either the inclination of the table or to allow for variation in the drag link gear and eccentric gear.

The belt which is made of duck "woven hard" is prepared by soaking it in oil and then thinly dressing it by spraying and scraping or distributing by means of rollers or in other convenient manner with another oil, one of said oils being a mineral oil and 5 the other a vegetable drying oil, the final dressing being so slight that the surface retains no appreciable amount of oil, only sufficient to render the surface slightly adhesive to the metal or valuable portions of the pulp 10 and scarcely apparent to the touch. By such means it is found that not only is the minimum amount of oil required for dressing the belt but the metal or valuable portions are retained without themselves retaining 15 any appreciable amount of oil, so that not only is the after process of separating the oil from the metal or valuable portions dispensed with but also allows of a simple means being provided for removing the 20 metal or valuable portions from the belt; for instance, by the use of a stream of compressed air, steam, or preferably by arranging a stream of water over the delivery end 25

of the belt so as to wash the contents off without materially affecting or dissipating 30 the oil coating.

What I claim as my invention and desire to secure by Letters Patent is:—

1. In an ore concentrating apparatus, a values collecting element composed of 35 "woven hard" duck soaked in an oil, and then thinly dressed with another oil, one of said oils being a mineral oil and the other a vegetable drying oil.

2. In an ore concentrating apparatus 40 a values collecting element composed of "woven hard" duck the surface of which is made slightly adhesive to the metallic parts of the pulp by treating it first with a drying oil and then with a mineral oil. 45

3. In an ore concentrating apparatus a values collecting element composed of "woven hard" duck soaked in linseed oil and then thinly dressed with mineral oil.

In testimony whereof I have signed my 50 name in the presence of two subscribing witnesses.

JACOB DAVID WOLF.
